UNITED STATES PATENT OFFICE.

EARL G. WATROUS, OF CHICAGO, ILLINOIS.

LIQUID-SOAP-DISPENSING DEVICE.

1,229,556.

Specification of Letters Patent. Patented June 12, 1917.

Application filed May 21, 1915. Serial No. 29,504.

To all whom it may concern:

Be it known that I, EARL G. WATROUS, a citizen of the United States, residing at Chicago, in the county of Cook and State of Illinois, have invented certain new and useful Improvements in Liquid - Soap - Dispensing Devices, of which the following is a specification.

My invention relates to a dispenser for liquid soap and the object thereof is to provide a simple and efficient device of this character. The construction is comparatively simple and capable of ready assembling and disassembling, particularly removal of the liquid container or receptacle for the purpose of replenishing the supply of soap and moreover the operation is simple and at all times reliable.

In the drawings Figure 1 is a central vertical section of my device; Fig. 2 a front elevation thereof, particularly in section and on a smaller scale than in Fig. 1; and Fig. 3 a bottom plan view of the cap of the container or receptacle.

Referring to the particular embodiment of my invention as shown in the drawing, the base or supporting member 1 is provided with a screw-threaded stem 2 which passes through the support 3 which may be the plate or slab of a basin. This base is attached or clamped to the support by means of the nut 4 screwing against the washer 5 interposed between it and the lower face of the support or plate 3. The base 1 is hollow and receives the combined push button and spout which is movable vertically in the base, the button portion being indicated at 6 and the spout portion 7.

The liquid container or receptacle 8, which may be of any desired shape but preferably the pear-shape shown, is supported from the shank 2 through the medium of the wire 9 and the cap 10. This cap is screw-threaded upon the shank 2 and provided with depending marginal flanges 10^a which overlap the top edges of the receptacle and which are provided at opposite sides with openings 10^b. These openings are adapted to receive the bent ends 9^a of the wire 9. This wire encircles the body portion of the receptacle and the free ends are connected with the cap 10 as just described, but is not in contact therewith except at the bottom whereat it is normally retained in the groove 8^a. By prefer-

ence a washer or gasket 11 is interposed between the top edges of the receptacle and the cap 10. According to this construction the liquid receptacle can be readily removed from the remainder of the fixture and can be readily attached thereto, it being understood that by springing in the opposite sides of the wire 9, the same becomes elongated and thereby released from the bottom of the receptacle with the result that the latter is free to be removed.

The stem 2 also carries the pump mechanism which comprises the pump cylinder 12, piston 13 reciprocable therein and hollow piston rod 14 which extends vertically and is connected at its upward end to the spout 7. The cylinder 12 is supported by the stem 2 by means of the tube 15 which is screw-threaded at its opposite ends to the stem 2 and the cylinder 12 respectively. The pump cylinder is provided with a bottom opening 16 which is controlled by a check valve 17 which is here in the form of a ball. The piston is normally upwardly pressed by means of a spring 18 interposed between the lower face of the piston and the bottom of the piston chamber.

The piston chamber is normally filled with liquid soap and upon the depression of the button 6 and spout 7 by the pressure of the operator's hand thereon the piston 13 is moved downwardly against the tension of the spring 18 and the soap therein is forced upwardly through the piston and piston rod 14 and out through its spout-shaped end and thereby dispensed for the operator or user.

When the operator permits the button 6 to move upwardly a new supply or charge of liquid soap is drawn upwardly through the inlet 16, the check valve 17 permitting such flow of soap into the piston chamber. The device is now ready for the next depression of the button and spout and this operation continues until sufficient soap has been dispensed. The pipe 15 is provided with a port 19 to drain back into the receptacle any liquid soap which may accumulate therein.

The device is removably attachable to any suitable support and may be arranged either in the vertical position shown, or in a horizontal position when obvious changes are made in shape of the receptacle to permit pumping from the bottom thereof. Moreover, my construction permits the spout and

operating button to be arranged on one side of the support and the receptacle on the other side and out of sight.

I claim:

5. 1. A liquid soap dispensing device comprising a base portion having a stem, a combined button and spout movably mounted in such base portion, a liquid soap receptacle removably secured to and supported by the 10 stem, a pump arranged in such receptacle and including a hollow piston rod extending through said base portion and said spout.
2. In combination with a suitable support, a liquid soap dispensing device comprising 15 a base portion clamped to the support, a combined button and spout movably mounted in such base portion and arranged on one side of the support, a liquid soap receptacle connected with and supported by said base 20 portion and arranged on the other side of the support, and pump mechanism arranged within the receptacle and communicating with said spout.
3. In combination with a suitable support, 25 a liquid soap dispensing device comprising a base portion having a stem extending through the support and clamped thereto, a combined button and spout movably mounted on and supported by such base portion
- 30 and arranged on one side of the support, a liquid soap receptacle removably connected with said stem and arranged on the other side of the support, and pump mechanism arranged within the receptacle and communicating with said spout.
4. In combination with a suitable support, 35 a liquid soap dispensing device comprising a base portion having a stem extending through the support and clamped thereto, a combined button and spout movably mounted in such base portion and arranged on one side of the support, a cap removably connected with said stem, a wire frame connected with the cap, a liquid soap receptacle 40 arranged within the wire frame and having its top closed by the cap, said receptacle being arranged on the other side of the support, and pump mechanism arranged within the receptacle and communicating with said 45 spout.
5. A liquid soap dispensing device comprising a base portion having a stem, a combined button and spout movably mounted in such base portion, a liquid soap receptacle, 50 a cap therefor attached to the stem, a wire frame passing around the body of the receptacle and having its free ends connected with

the cap, and pump mechanism arranged in such receptacle and communicating with said spout.

6. A liquid soap dispensing device comprising a base portion having a stem, a combined button and spout movably mounted in such base portion, a liquid soap receptacle, a cap therefor attached to the stem, a wire frame passing around the body of the receptacle and having its free ends connected with the cap, said frame contacting the receptacle only at the bottom thereof, and pump mechanism arranged in such receptacle and communicating with said spout. 65

7. A liquid soap dispensing device comprising a base portion having a stem, a combined button and spout movably mounted in such base portion, a liquid soap receptacle, a cap therefor attached to the stem, a wire frame passing around the body of the receptacle and having its free ends connected with the cap, said receptacle having on its bottom a groove in which the wire frame is normally 70 held, such frame being free of the receptacle at other points, and pump mechanism arranged in such receptacle and communicating with said spout.

8. A liquid soap dispensing device comprising a base portion having a stem, a combined button and spout movably mounted in such base portion, a liquid soap receptacle, a cap therefor attached to the stem and having marginal flanges provided with holes on 80 opposite sides, a wire passing around the body of the receptacle and having its free ends bent and arranged to enter said holes, and pump mechanism arranged in such receptacle and communicating with said spout. 95

9. A liquid soap dispensing device comprising a base portion having a stem, a combined button and spout movably mounted in such base portion, a liquid soap receptacle removably secured to and supported by the 100 stem, a pump arranged in such receptacle and including a pump cylinder arranged near the bottom of the receptacle and having a check valved inlet, a piston reciprocable in such cylinder, a hollow piston rod 105 having one end extending through the piston and having its outer end communicating with said spout, and means for holding the piston and spout in upward position with a yielding pressure.
